UNITED STATES PATENT OFFICE.

EDWARD C. HULSE, OF SPRINGFIELD, MISSOURI.

NAIL-SET HAMMER.

1,143,277.

Specification of Letters Patent. Patented June 15, 1915.

Application filed August 3, 1914. Serial No. 854,702.

To all whom it may concern:

Be it known that I, EDWARD C. HULSE, a citizen of the United States, resident of Springfield, in the county of Greene and State of Missouri, have made a certain new and useful Invention in Nail-Set Hammers; and I declare the following to be a full, clear, and exact description of the same, such as will enable others skilled in the art to 10 which it appertains to make and use the invention, reference being had to the accompanying drawings, and to letters or figures of reference marked thereon, which form a part of this specification.

15 Figure 1 is a perspective view of the hammer showing the nail. Fig. 2 is a similar view of the hammer with one spring plate removed. Fig. 3 is a detail perspective view of one of the spring plates having the nail 20 gripping jaw. Fig. 4 is a central longitudinal section of the hammer.

The invention has relation to improvements in nail set hammers adapted to grip the nail and to set the same in the work by 25 a stroke of the hammer, and it consists in the novel construction and combinations of parts, as hereinafter set forth.

In the accompanying drawings, illustrating the invention, the numeral 2 designates 30 the hammer head, having the nail driver 3 at one end and the extracting claw 4 at the other end. The claw end of the hammer is provided with shallow lateral open-top and open-end recesses 5, 5, bounded at the inner 35 ends by walls or shoulders 6, 6, and at the bottom by walls or shoulders 7, 7; and with an end open-top and open-end recess 8, bounded at the inside by a wall or shoulder 9 and at the bottom by a wall or shoulder 10, 40 an open-top recess 11 leading into said end recess and having a bearing shoulder 11' in rear of its top opening.

Fitting in each lateral recess, against the flat sides 12 thereof, is a spring plate 13, 45 bearing at its inner end 14 against the shoulder 6, and at its bottom 15 against the shoulder 7, the spring plates having at their outer ends substantially triangular prismatic jaws 16, 16, projecting toward each 50 other, closing the outer end of the recess 8 of the hammer head and provided at their approximated ends with central toothed portions 17, 17, the teeth of which extend longitudinally of the hammer head and are 55 designed to grip and hold the shank of a

nail, shown at 18, so that upon a stroke of the hammer the nail will be set in the work.

The top edges of the spring plates and the outer or top edges of the jaws are rounded to conform with the top surface of the 60 claw end of the hammer head, which may thereby be rocked in the usual way upon its cam top surface in extracting a nail, the jaws 16, bearing at their inner sides 19, 19 against the shoulders 9, and at their bottoms 65 against the shoulders 10 take the strain from the comparatively thin spring plates. Each spring plate has its inner edge 14 and its oblique bottom edge 15 preferably at an acute angle relation to each other and meeting at an acute angle 21 and fitting closely against the inner and bottom shoulders of 70 the lateral recess.

In operation, the nail shank is pressed into the top of the recess 11, against the 75 rounded or beveled corners 16' of the jaws, to force said jaws apart, the jaws closing by inherent spring pressure to grip the nail shank by the toothed portions of the jaws, the teeth of said portions being in line with 80 the nail. A stroke of the hammer will now bring the nail head against the end wall of the top recess, beneath the shoulder 11; and at the same time will set the nail properly 85 in the work. A slight tilt of the hammer now serves to release the nail from the jaws, the head of the nail taking a fulcrum bearing against the said shoulder 11'. The nail is then driven home by reversing the hammer head and striking the nail with the nail 90 driver end of the hammer.

It is designed in this device to adapt the nail setting device to the hammer without marked change in the conformation thereof or interference with the cam top surface of 95 the head used in extracting nails, retaining also the well balanced character of the hammer head. The claw end of the hammer, being adjacent to the nail setting device, is in convenient position for the withdrawal of 100 an improperly set nail.

What I claim is:

1. A nail placer, comprising a hammer head having a claw end provided with a curved top surface, an end recess provided 105 with bottom and inner walls, and a top recess leading into said end recess and having a bearing shoulder in rear of its top opening, spring plates secured to the sides of said claw end and having at the outer ends 110

thereof toothed nail-gripping jaws projecting toward each other across the open end of said end recess, said jaws bearing against the bottom and inner walls of said end recess, and said spring plates and said jaws having top surfaces conforming to and in continuation of the curve of the top surface of the hammer.

2. A nail placer, comprising a hammer head having a claw end provided with a curved top surface, lateral recesses, an end recess provided with bottom and inner walls, and a top recess leading into said end recess and having a bearing shoulder in rear of its top opening, spring plates located within said lateral recesses and secured to the sides of said claw end and having at their

outer ends substantially triangular prismatic toothed nail-gripping jaws projecting toward each other across the open end of said end recess, said jaws bearing against the bottom and inner walls of said end recess, to take the strain from said spring plates and said spring plates and said jaws having top surfaces conforming to and in continuation of the curve of the top surface of the hammer.

In testimony whereof I affix my signature, in presence of two witnesses.

EDWARD C. HULSE.
